UNITED STATES PATENT OFFICE.

TATSUKICHI ENOCHTY, OF NEW YORK, N. Y.

DISPLAY-STAND.

1,242,429.

Specification of Letters Patent.

Patented Oct. 9, 1917.

Application filed October 25, 1916. Serial No. 127,588.

To all whom it may concern:

Be it known that I, TATSUKICHI ENOCHTY, a subject of the Emperor of Japan, residing at New York city, in the county and State 5 of New York, have invented certain new and useful Improvements in Display-Stands, of which the following is a specification.

My invention relates to advertising signs, of the kind usually placed on the house 10 tops and at road sides for use in advertising.

A sign of this character usually consists of long sheet iron plates upon which the desired advertising matter is painted. It has been found in practice that such sheet 15 metal signs are subject to considerable expansion and contraction, according to conditions of temperature and weather. The result of such expansion and contraction is that the paint, which is generally laid on 20 fairly thickly, breaks and peels off, thus spoiling the desired effect.

The principal object of my invention is to provide an improved advertising sign of this kind in which the defect above pointed 25 out is obviated.

I accomplish my object by providing the sign throughout substantially its entire extent with a series of perforations or breaks, the effect of which is that the paint will 30 not break or peel off, and if the sign does expand or contract the general effect of the painting thereon will be preserved and if any cracks develop they will be of such minute character as not to be visible except 35 upon close inspection, and will not detract from the general appearance and effect of the painted advertising.

By providing the breaks or projections, as suggested above, I divide the surface of 40 the sign into a large number of relatively small intact areas, in none of which the molecular movement of the metal due to temperature changes is appreciable to any substantial degree. Hence, expansion and 45 contraction if any, are limited to these small intact areas, and the appearance of the sign as a whole is not substantially altered.

The preferred form of perforations is triangular and may be made by stamping 50 triangular tongues out of the metal and bending such tongues slightly out of the

plane of the sign. I have also found it desirable to apply a coat of paint to the rear of the sign which, to some extent, assists in preventing distortion of the metal. 55

One of the numerous forms in which the invention may be embodied is illustrated in the accompanying drawing in which—

Figure 1 is a front elevational view of my improved sign; and 60

Fig. 2 is a vertical sectional view on the line 2—2 of Fig. 1.

In the drawing 10 denotes a support such as a fence or a house top upon the upper edge of which are standards 11 which support the sign 12. The sign consists of a sheet of galvanized iron of suitable length and width, such sheet being provided throughout its extent with openings or perforations 13, which are preferably formed, 65 as indicated in the drawing, by punching out triangular tongues and bending them slightly rearwardly out of the plane of the sheet 12. Upon the face of the sign the desired advertising matter 14 is painted, this 70 advertising matter being usually superimposed on a coat of paint 15 which is first applied to the front face of the sheet 12. 75

The rear face of the sign may be covered with a coat of paint 16 which, for reasons 80 not entirely known to me, restrains the tendency of the sign to distort under the effect of temperature and weather changes.

As above indicated, the form of the openings 13 shown in the drawing is the 85 preferred one, but I do not desire to be limited to such form.

What I claim as new and desire to secure by Letters Patent is:—

1. An advertising sign, consisting of a 90 sheet of metal, having openings therein throughout its extent, a coat of paint upon at least one face of said sheet, and advertising matter superimposed on said coat of paint. 95

2. An advertising sign comprising a sheet of metal having tongues cut therefrom and bent out of the plane of said sheet to form openings throughout the entire extent of the latter, a coat of paint upon at least one 100 face of said sheet, and advertising matter superimposed on said coat of paint.

3. An advertising sign comprising a sheet of metal having triangular tongues stamped out therefrom throughout its extent and bent out of the plane of the sheet, a coat of
5 paint upon at least one face of said sheet, and advertising matter painted on said coat of paint.

4. An advertising sign consisting of a

sheet of galvanized metal having openings formed therein and painted on both sides. 10

In testimony whereof I have affixed my signature in presence of two witnesses.

TATSUKICHI ENOCHTY.
